REFRIGERATOR CABINET

William E. Richard, Galesburg, Ill.

Application September 19, 1935, Serial No. 41,249

6 Claims. (Cl. 62—116)

This invention relates to improvements in refrigerator cabinets. It has for its principal object the reduction in the overall apparent height of the cabinet as compared with present cabinets.

5 Another object is to increase the size of the food compartment without increasing the overall size of the cabinet.

A further object is to provide a neat and inexpensive machine compartment cover, the operating parts being thereunder and totally enclosed thereby.

Other objects will be apparent from the following specification.

The invention consists substantially in the construction, combination, location and relative arrangement of parts, all as will be more fully hereinafter set forth and as shown by the accompanying drawing and finally pointed out in the appended claims.

20 In the drawing:

Figure 1 is a front view of a cabinet embodying the invention; and

Figure 2 is a side view of the cabinet shown in Figure 1.

25 The numeral 10 denotes a refrigerator cabinet the walls of which are heat insulated in any suitable manner. This cabinet has the usual food compartment 11 closed by the usual door 12. The top wall of the food compartment has a 30 central aperture or well 13 therein adapted to receive a unit base 14, which spans the aperture, the edges of said base being supported on the cabinet walls. The front wall extends upwardly as shown at 10^a, the portion 10^b thereof forming 35 a support for the front edge of the base 14. The side walls extend upwardly as shown at 10^c, 10^d, the portions 10^e and 10^f supporting the side edges of base 14. The rear wall 10^g is cut off as shown in Figure 2 so that the back of the cabinet above 40 10^g is open to take the condenser 18 and flue 19 to be presently described and to provide an outlet at each side of the condenser for cooling air, which may be drawn through the condenser and discharged around the sides thereof, suitable 45 baffles (not shown) being provided to direct the air flow.

On base 14 is supported in any suitable manner a compressor unit 15 comprising a pump or compressor and a driving motor therefor, preferably directly connected. As such units are well known and may be of any suitable construction, the unit is not described in detail.

Secured to this same base 14 and supported thereby is a motor 16 for driving a cooling fan 55 enclosed in housing 17 of sheet metal for the

purpose of cooling a condenser 18 of any suitable construction attached to the rear ends of base 14 which is cut out to straddle the condenser which lies partially in a plane with the rear wall of the cabinet.

Attached to the rear edge of base 14 is a metal flue or duct 19 open at 20.

In some forms of construction the motor 16 and fan connected thereto are omitted, the condenser 18 being cooled by direct radiation only, 10 or the cooling fan is mounted on the unit 15. Secured to the bottom of 14 is a metal casing 21 for the bottom of the compressor unit 15 and spaced apart from 21 so as to have an intervening air space for heat insulation forming 15 where the base 14 is in place, a portion of the top insulating wall of the food compartment 11.

Attached to the bottom of wall 22 are the 20 brackets 23 and 24 supporting the usual evaporator 25 located within the food chamber 11.

All of the spaces above the wall 22 may be termed the machine compartment. The space 21 may be in communication with the space above the base 14 by means of apertures 26 and 27 25 therein so that free circulation of air may occur about the bottom of the compressor unit 15. The space 21' may be packed with heat insulation, or may be left open for air circulation.

The top of the cabinet is provided with a machine compartment cover 28 which fits over the upwardly projecting front and side walls of the cabinet. This cover has laterally extending side portions 29 and 30 in which are louvres or holes 31 to permit air to circulate. The fan 17 may 35 draw air in at 20 and discharge same through the louvres or the air flow can be reversed.

The cover 28 fits snugly around the housing for condenser 18 which together with flue 19 forms the back of the machine compartment. 40

The cover 28 has a central portion 32 adapted to receive the top of the unit 15, the entire cover being shaped as shown in the figures to have an attractive appearance and to remove the objection of an upwardly extending and exposed 45 machine unit.

The usual connections between the compressor unit, the cooling fan, condenser and evaporator are not shown as these are obvious to those skilled in the art. Insulation such as rubber 50 gaskets can be inserted at 33, 34, 35 and 36 to prevent heat leakage from the machine compartment to the food compartment. Instead of the wall 22 being made of sheet metal and filled 55 with insulation in the usual manner, this

U-shaped piece can be made of moulded composition of a heat insulating character with resilient gaskets at 33, 34, 35 and 36 so as to effectively seal the machine compartment from the food compartment.

The cover 28 can be lifted off for inspection, and if necessary the base 14 carrying all the working parts can be lifted out of the cabinet.

It will be apparent that by providing the top 10 of the cabinet with the central aperture or well 13, and locating the mechanism partly therein and partially below the upper edges 10^a, 10^c and 10^d of the cabinet walls, that the overall height of the cabinet is reduced as compared with refrigerators in which the machine compartment is either located below the food compartment near the floor, or above the top wall of the food compartment. In the latter case the compressor unit projects above the cabinet and the condenser wrapped about the same is usually exposed or a shroud is necessary. The objections present in both said types of construction are eliminated by the present invention without adding to the cost of the complete refrigerator. 25 Although the invention has been disclosed in connection with the specific details of preferred embodiments thereof, it must be understood that such details are not intended to be limitative of the invention except insofar as set forth in the accompanying claims.

What is claimed is:

1. A refrigerator comprising a cabinet having an aperture in its top insulating wall, a base adapted to span said aperture, refrigerating mechanism mounted on said base and extending downwardly into said aperture below the upper edges of the side walls of the cabinet, a wall of insulating material supported by said base and spaced apart from said mechanism and extending downwards into said aperture and adapted to close the same and complete therewith the top insulating wall of the cabinet, and an evaporator carried on said wall subjacent thereto.

45 2. The combination as claimed in claim 1

wherein the base supports a condenser positioned in a plane with the rear wall of the cabinet at the top thereof.

3. The combination as claimed in claim 1 wherein the base supports a flue at the rear 5 of the cabinet, said flue extending below the upper edge of the rear wall of the cabinet.

4. The combination as claimed in claim 1 wherein the cabinet is provided with a cover adapted to enclose the refrigerating mechanism. 10

5. A refrigerator comprising a cabinet having a food compartment with insulated walls and an aperture in the top wall of said compartment, a base adapted to span said aperture, refrigerating mechanism mounted on said base outside said 15 food compartment said mechanism having a part extending downwardly below the upper edges of the side walls of the cabinet, a wall of insulating material supported by said base and spaced apart from said mechanism extending downward below and underneath said mechanism into said food compartment, a casing about said mechanism and positioned between a vertical side wall thereof and said wall of insulating material supported on said base, and an evaporator 25 in said food compartment and forming with said mechanism a structure adapted to be removed as a unit from the cabinet.

6. A refrigerator comprising a cabinet having a food chamber therein, said chamber having 30 a top insulating wall and an aperture in said wall, a base adapted to span said aperture, a refrigerating unit including a compressor spaced apart from said top insulating wall and supported by said base in the aperture in said wall, and 35 driving means therefor, and an evaporator supported by said base, a condenser mounted on said base, a flue connected to said base and extending downwardly at the rear of said cabinet to a point below the upper edges of the walls 40 of the food chamber, and a top for said cabinet surrounding and enclosing said condenser and compressor.

WILLIAM E. RICHARD.
